WATER SKI

Arthur E. Liebscher, Laguna Hills, Calif., assignor
to W. J. Voit Rubber Corporation, a corporation
of California

Filed Aug. 30, 1966, Ser. No. 3,648

Term of patent 14 years

(Cl. D71—1)

FIG. 1

FIG. 2

FIG. 3

FIG. 4

FIG. 5

FIG. 1 is a perspective view of a water ski showing my new design;

FIG. 2 is a perspective view showing the bottom of said water ski;

FIG. 3 is a cross section taken along the line 3—3 of FIG. 1;

FIG. 4 is a side elevation view showing the subject water ski; and

FIG. 5 is a bottom plan view showing the water ski.

In view of the prior art, the characteristic features of my design reside in the overall appearance resultant from the association of the general shape with the specific configuration of the bottom area of the water ski, as best seen in FIGS. 1, 2 and 3.

I claim:

The ornamental design for a water ski, as shown.
